Primary Examiner — Elizabeth J Oswecki

(57) **CLAIM**

The ornamental design for a light, as shown and described.

DESCRIPTION

FIG. 1 is a perspective view of a light showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another perspective view of the light, where the light is in a configuration of use.

The even dashed broken lines represent unclaimed environment and form no part of the claimed design. The dash-dot lines represent light rays in FIG. 9 and form no part of the claimed design.

The oblique line shading represents a reflective, luminous, refractory surface.

1 Claim, 9 Drawing Sheets
